DENTAL IMPRESSION TRAY

Gaylon T. Westlund, 4732 Virginia Ave. N., Minneapolis, Minn. 55428, and Nels E. Neslund, 4241 N. Twin Oak Lane, Robbinsdale, Minn. 55422

Filed Mar. 28, 1967, Ser. No. 6,408

Term of patent 14 years

(Cl. D24—1)

FIG. 1 is a perspective view of a dental impression tray showing our new design;

FIG. 2 is an elevational view of the tray as seen from the right side;

FIG. 3 is a bottom plan view of the tray;

FIG. 4 is an end elevational view of the tray as seen from the tab end;

FIG. 5 is an elevational view of the tray as seen from the left side;

FIG. 6 is a perspective view of a modified embodiment of the dental tray shown in FIG. 1;

FIG. 7 is a side elevation thereof;

FIG. 8 is a bottom plan view thereof;

FIG. 9 is an elevation as seen from the tab end of the tray; and

FIG. 10 is an elevation as seen from the opposite side of FIG. 7.

We claim:

The ornamental design for a dental impression tray, as shown and described.
